[57] ABSTRACT

A reversing valve for refrigeration and air conditioning systems which is operable to reverse the flow of refrigerant through the heat exchangers which function as the condenser and evaporator in the system. A solenoid plunger assembly is utilized to control the reversing action, and it is mounted on the reversing valve in an arrangement which minimizes heat loss from the coil and which improves the armature action. An arrangement is also provided to assure desired pressure conditions on opposite sides of moving parts so that more effective operation of the valve occurs.

REVERSING VALVE ASSEMBLY

BACKGROUND OF THE INVENTION

The present invention relates to an improved reversing valve for use in refrigeration and air conditioning systems.

It is known in some refrigeration systems to provide for selectively reversing the direction of flow of refrigerant in order to effect periodic heating of a particular heat exchanger in the system, thereby changing the function of the heat exchanger from an evaporator to a condenser for the purpose of quickly melting frost or ice which may have collected thereon in the case of a refrigerator, or heating the interior of a room during cooler periods of weather, in the case of an air conditioner. The term "refrigeration systems" as used hereinafter, is inclusive of air conditioning systems.

One type of prior art reversing valve of which the present invention is an improvement is disclosed in applicant's prior U.S. Pat. No. 3,293,880, issued Dec. 27, 1966. The present invention provides an improved arrangement of the solenoid assembly so that the solenoid is more effectively mounted out of heat transfer relationship with respect to the refrigerant that flows through the reversing valve. Also, an improved spring arrangement is provided for returning the armature of the solenoid to its normal position after the coil is deenergized. Still other improvements are found in the arrangement for bleeding refrigerants from the valve passage on opposite ends of the floating piston provided therein for reversing the direction of flow in the system. Improvements have also been provided whereby the pressures on the opposite ends of movable parts are more effectively balanced to assure proper movement of such parts.

Accordingly, it is among the objects of the present invention to provide an improved reversing valve for refrigeration systems which is constructed and arranged to minimize heat losses, which provides for more effective balancing of the pressures on opposite sides of moving parts so that such parts can move in the most desirable manner, and which has improved bleeding characteristics within piston chambers to assure movement of the floating piston in the optimum manner.

According to a preferred form of the present invention, a reversing valve is provided comprising a valve body having a substantially straight passage therein, header means on said body defining the ends of said passage, a pair of fluid inlets in communication with said passage adjacent to the ends thereof, a first port intermediate said ends, a pair of second ports located on opposite sides of said first port, a piston slidably supported in said passage for movement between a first limit-position adjacent to one end of said passage and a second limit-position adjacent to the other end of said passage. The inlets are located so that they are in communication with opposite ends of the piston in both limit-positions, and said piston is shaped so as to define with the passage a chamber providing communication between the first port and one of said second ports when the piston is in its one limit-position and between the first port and the other of said second ports when the piston is in the other limit-position. The header means at each end includes a normally open bleed port each of which is in communication respectively with one of said second ports and a valve member for each bleed port responsive to movement of the piston to its adjacent limit-position to close said bleed port. Supply means are provided for supplying fluid under pressure to the passage only through one or the other of said inlets.

The supply means includes a second passage in the body in communication with the two inlets at longitudinally spaced intervals of the second passage. The body has a fluid inlet port to said second passage between the inlets and a valve element is longitudinally movable therein to positions on opposite sides of said inlet port for selectively directing the fluid from the inlet port to one or the other of said inlets. A solenoid assembly is connected to the valve element normally pressing the valve element to one side of the inlet port and it is operable when electrically energized to move the valve element to

the other side of the inlet port. The solenoid assembly includes a sleeve extending into one end of the second passage and an armature housed within the sleeve and connected to said valve element. A coil is mounted on the sleeve beyond the end of the second passage so as to be substantially out of heat transfer relationship with the interior of the second passage. A spring is operably mounted in the second passage to bias the valve element to one side of the inlet port. The valve element is dimensioned to provide leakage between its outer periphery and the bore of the second passage to provide substantially balanced pressures on opposite sides thereof. Thus, the solenoid assembly is substantially out of heat transfer relationship with respect to the second passage, and the spring arrangement and the dimensions of the valve element are such as to require minimum energy to move the element between its two positions. The relationship of leakage past the valve element and the rate at which bleeding can occur from the ends of the first passage is such as to minimize the possibility of the floating piston in the first passage being obstructed in its movement from one end to the other end when it is desired to reverse the flow of the refrigerant.

Other objects of this invention will appear in the following description and appended claims, reference being had to the accompanying drawings forming a part of this specification wherein like reference characters designate corresponding parts in the several views.

BRIEF DESCRIPTION OF THE DRAWING

FIG. 1 is a schematic illustration of a refrigeration system, showing the reversing valve assembled in the system and in a position in which it provides for flow of refrigerant in one direction through the heat exchangers in the system, with the reversing valve in certain parts of the system being shown in section for the purpose of clarity;

FIG. 2 is a schematic illustration similar to FIG. 1, showing the reversing valve in a position for reversing the flow of refrigerant through the heat exchangers in the system;

FIG. 3 is an enlarged fragmentary section of one end of the first passage in which the floating piston is located, showing details of the header and bleeder arrangement;

FIG. 4 is a section taken on the lines 4-4 of FIG. 3;

FIG. 5 is an exploded view of one end of the floating piston; and

FIG. 6 is a longitudinal section on the axis of the one end of the floating piston.

DESCRIPTION OF THE PREFERRED EMBODIMENT

Before explaining the present invention in detail, it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

With reference to the drawings, the improved reversing valve of this invention, indicated generally at 10, is illustrated in FIG. 1 in a refrigeration system 12 which includes a conventional compressor 14 and heat exchangers 16 and 18, both of which are capable of functioning either as a condenser or an evaporator. A conventional flow restriction tube 20 connects the heat exchangers 16 and 18. The compressor 14 has its discharge connected by a conduit 22 to the inlet port 24 for reversing valve 10. A conduit 26 connects the outlet port 28 for reversing valve 10 with the suction inlet of the compressor 14.

In the illustrated embodiment of the invention, the reversing valve 10 includes a valve body 30 having a first passage 31 closed at its ends by headers 32 and 34 and formed intermediate its ends with the discharge port 28. A pair of ports 36 and 38 are formed in the valve body 30 on opposite sides of the discharge port 28, with the port 36 being connected by a

conduit 40 to the heat exchanger 16, and the port 38 being connected by a conduit 42 to the heat exchanger 18. Adjacent to the header 32, the valve body 30 is formed with an inlet 44, and adjacent to the header 34, the valve body 30 is formed with another inlet 46.

The valve body 30 has a second passage 48 which is in communication at its opposite ends with the inlets 44 and 46 which are located on opposite sides of the inlet port 24. One end of the passage 48 is closed by the end plate 50, and the other end is closed by the end plate 52. A solenoid assembly 54 is mounted on one end of the valve body 30 and includes a sleeve 55 for housing the armature 56. As can be seen in FIG. 1, the sleeve 55 extends into the passage 48 into abutment with the one end plate 52. The armature 56 is connected to a valve element 58, and a spring 60 is operatively positioned between the disk portion 62 and the end plate 52 for normally urging the disk portion to the position shown in FIG. 1. The valve element 58 includes the rod 64 which is affixed to the disk portion 62 and to the armature 56 so that these parts move as a unit within the passage 48. It will be understood that when the coil of the solenoid assembly 54 is energized, the valve element 58 will move to the position shown in FIG. 2, and when the coil is deenergized, the coil spring 60 will function to move the element 58 to the position shown in FIG. 1. Thus, when the valve element 58 is in the position shown in FIG. 1, refrigerant can flow from the inlet port 24 through the second passage 48 to the inlet 46 for the first passage 31, and when the solenoid assembly 54 is energized, and is in the position shown in FIG. 2, the refrigerant can flow from the inlet port 24 through the second passage 48 to the inlet 44 for the first passage 31.

In the illustrated embodiment of the invention, the disk portion 62 has a peripheral dimension smaller than that of the bore of the second passage 48 so that leakage of refrigerant will occur around the periphery of the disk portion 62 to maintain the fluid pressure on opposite sides of the disk substantially equal. By minimizing pressure differences on opposite sides of the disk portion 62, the most reliable and optimum functioning of the solenoid assembly 54 and its associated valve element 58 are assured. It will also be noted that the solenoid assembly 54 is mounted in a position where it is substantially out of heat transfer relationship to the passage 48 so that when the coil of the solenoid assembly 54 is energized, very little heat will be transferred to the refrigerant, thereby assuring optimum efficiency of the system.

A free floating piston 66 is slidably supported in the first passage 31. The piston is an integral construction having two axially spaced cylindrical portions 68 and 70, of a diameter to be slidably supported in the valve body 30, and a reduced diameter stem portion 72 which connects the cylinder portions 68 and 70. The cylinder portion 68 is formed with an axially outwardly extending cup-shaped projection 74 and the cylinder portion 70 is formed with a similar axially outwardly extending cup-shaped projection 76.

The header 32 which is mounted on one end of the passage 31 has a bleed port 78 centrally located therein and bleed ducts 80 and 82 are provided respectively in the header 32 and the valve body 40 to discharge into the port 36. Similarly, the header 34 has a centrally located bleed port 84 and ducts 86 and 88 provide communication with the port 38. Also mounted on the header 32 is a needle valve 90 which is spring biased by the spring 92 to a normally open position and which can be moved axially to close the bleed port 78. As can be seen best in FIGS. 3 and 4, the needle valve is mounted on the annular ring 94 which is seated and secured in the end of the header 32 and has a plurality of apertures 96 therein to permit flow of fluid from the passage 31 through apertures 96 into bleed port 78 and from there through ducts 80 and 82 to the port 36.

A similar needle valve 98 is mounted on the header 34 for closing the bleed port 84. In FIG. 1, the needle valve 98 is shown in its closed position, having been urged to this position by movement of the piston 66 to its one limit position. At the

same time, the needle valve 90 in the header 32 is in its open position. Thus, when the coil of the solenoid assembly 54 is deenergized, the flow of the refrigerant will be as is shown by the indicator arrows in FIG. 1.

If it is desired to reverse the direction of flow of the refrigerant to follow the flow circuit shown by the indicator arrows in FIG. 2, the coil of solenoid assembly 54 will be energized causing the valve element 58 to move to the limit-position shown in FIG. 2. This will have the effect of applying the full pressure of the refrigerant fluid on the right side of the floating piston 66 while at the same time substantially reducing fluid pressure from the left side of floating piston 66. Initially, needle valve 98 will be in its closed position and needle valve 90 will be in its open position to assure maximum pressure differential on opposite sides of piston 66, and open needle valve 90 will allow escape of the fluid trapped on the left side of piston 66 via the bleed port 78. When the refrigerant fluid has completed movement of piston 66 to the position shown in FIG. 2, the flow of refrigerant fluid will have been reversed through the heat exchangers 16 and 18, as indicated.

The first passage 31 is undercut at the two ports 36 and 38 so that when the piston 66 is reversed, it is free floating while passing over the ports 36 and 38 to prevent stalling while moving from one limit-position to the other limit-position. Also, the bleed lines at each header 32 and 34 have about six times the capacity as the leakage rate permitted around the disk portion 62 to provide an ample safety factor when the reversing operation is to be carried out.

To assure that a proper seal is provided between the high and low pressure sides of the piston 66, a preferred construction is shown in FIGS. 5 and 6. As there shown, the stem portion 72 has secured thereon the collar 100 against which is seated the cylindrical portion 68. Positioned on the stem portion 72 between the collar 100 and the cylindrical portion 68 is a Teflon seal ring 102, and located within the seal ring 102 is an annular metallic spring 104 which constantly urges the seal ring radially outwardly. Thus, the seal ring 102 is constantly urged into a snug fit with the first passage 31.

It is claimed:

1. In a reversing valve, a valve body having a substantially straight passage therein, headers on said body defining the ends of said passage, a pair of fluid inlets in communication with said passage adjacent to the ends thereof, means for supplying fluid under pressure to said passage only through one or the other of said inlets, a piston slidably supported in said passage for movement between a first limit-position adjacent to one end of said passage and a second limit-position adjacent to the other end of said passage, said inlets being located so that they are in fluid communication with opposite ends of said piston in both limit-positions of said piston, means on each of said headers forming a normally open bleed port and a valve member for each bleed port movably mounted on the header therefor and responsive to movement of said piston to its adjacent limit-position to close said bleed port, said valve member extending axially away from said bleed port, and spring means urging said valve member to an open position, one end of said valve member being engageable by said piston to urge said valve member to a position closing said bleed port.

2. In a reversing valve, the combination as is defined in claim 1, wherein said valve body has a first port intermediate the ends thereof and a pair of second ports located on opposite sides of said first port, and said bleed ports being in constant communication respectively with said second ports.

3. In a reversing valve, the combination as is defined in claim 2, wherein the inner periphery of said passage is undercut around its circumference at each of said second ports to provide a free floating condition of said end portions when passing over such ports.

4. A reversing valve comprising a valve body having a substantially straight passage therein, headers on said body defining the ends of said passage, a pair of fluid inlets in communication with said passage adjacent to the ends thereof, a

port intermediate said ends, a pair of second ports located on opposite sides of said first ports, a piston slideable supported in said passage for movement between a first limit-position adjacent to one end of said passage and a second limit-position adjacent to the other end of said passage, said inlets being located so that they are in communication with opposite ends of said piston in both limit-positions of said piston, said piston being shaped so as to define with said passage a chamber providing communication between the first port and one of said second ports when the piston is in its one limit-position and between the first port and the other of said second ports when the piston is in its other limit-position, each of said headers forming a normally open bleed port in communication with one of said second ports and a valve member for each bleed port movably mounted on the header therefor and responsive to movement of said piston to its adjacent limit-position to close said bleed port, and supply means for supplying fluid under pressure to said passage only through one or the other of said inlets, and comprising a second substantially straight passage in said valve body in communication with said pair of fluid inlets said body including an inlet port positioned between said inlets, a valve element movable longitudinally of said passage to opposite sides of said inlet port for selectively directing fluid to one or the other of said inlets and having a disk portion with a smaller transverse dimension than the transverse dimension of said second passage to permit leakage of fluid past said disk to produce pressure balance on opposite sides of said disk.

5. A reversing valve as is defined in claim 5, wherein the effective area for leakage of fluid past said disk portion is sub-

stantially less than the effective area for flow of fluid past said disk portion is substantially less than the effective area for flow of fluid from each bleed port to its associated second port.

- 5 6. In a reversing valve having a body with a first passage, first and second inlets to said first passage and a piston in said first passage for reversing flow of fluid therethrough, supply means for supplying fluid under pressure to said first passage only through one or the other of said inlets comprising a second passage in said body in communication with said inlets at a longitudinally spaced interval, said body having a fluid inlet port to said second passage between said inlets, a valve element longitudinally movable in said second passage to positions on opposite sides of said inlet port for selectively directing fluid from said inlet port to one or the other of said inlets, and a solenoid assembly connected to said valve element normally biasing said valve element to one side of said inlet port and operable when electrically energized to move the valve element to the other side of said inlet port, said solenoid assembly including a sleeve extending into one end of said second passage, an armature housed within said sleeve and connected to said valve element, a coil mounted on said sleeve beyond the end of said second passage, and a spring operably mounted in said second passage to bias said valve element to one side of said inlet port, said valve element being dimensioned to be smaller than the bore of said second passage to provide substantially balanced pressures on opposite sides of said valve element.
